EXHAUST TREATMENT DEVICE WITH AIR COMPRESSOR REGULATOR

Wright Wesley Gary, 2317 Kimbridge Road, Beverly Hills, Calif.

Filed Nov. 25, 1960, Ser. No. 71,473
12 Claims. (Cl. 60—30)

The present invention relates to air compressors or pumps, and it relates particularly to a novel compressor-regulator combination adapted to furnish fresh air to the exhaust system of an internal combustion engine to promote oxidation of unburned hydrocarbon and carbon monoxide exhaust components in anti-smog apparatus associated with the exhaust system.

Exhaust gases from internal combustion engines, and particularly from automobile engines, contain some unburned hydrocarbons which accumulate in the atmosphere and react to sunlight to form "smog" which causes eye irritation, is harmful to agricultural production, and appears to be a substantial human health hazard. Such exhaust gases also include carbon monoxide which, although not appearing to be a smog producing agent, is a poisonous gas and as such constitutes a considerable health hazard. A great deal of effort has been expended in recent years in the development of anti-smog apparatus. One form of such apparatus is the "afterburner" for direct burning of the undesired materials at temperatures above 2000° F. Another form is the "catalytic converter" for catalytically oxidizing or burning the unwanted materials at temperatures above about 500° F. In my copending application Serial No. 27,721, filed May 9, 1960 for Catalytic Converter System for Internal Combustion Engines I have illustrated, described and claimed apparatus for oxidizing the unburned hydrocarbon and carbon monoxide components of the engine exhaust by a novel combination of direct ignition burning and catalytic oxidation, which I have found to provide much more efficient oxidation of these unwanted exhaust components over the entire range of engine operating conditions than either an "afterburner" or a "catalytic converter" used alone.

Regardless of the type of apparatus employed for oxidizing the hydrocarbon and carbon monoxide components of the engine exhaust, whether it be an "afterburner," a "catalytic converter" or apparatus such as that described in my said copending application Serial No. 27,721 involving both direct ignition burning and catalytic oxidation, it is necessary to introduce fresh air into the exhaust line upstream of the oxidizing apparatus in order to support the combustion or oxidation of the unwanted exhaust components. I have found in practice that the most practical source of supply of fresh air for the exhaust system is an air compressor or pump of the positive displacement type which is driven by the engine fan belt. However, the air requirements for efficient oxidation of the unburned hydrocarbons and carbon monoxide in the exhaust system at relatively high speeds, as in freeway driving, are only slightly greater than the requirements at engine idle speeds so that the air compressor must include means for controlling the compressor output rate to a relatively small increase upon relatively large increases in engine speed.

The following example illustrates some of the factors which must be considered in connection with the air supply source. This example is based upon the use of a 235 cubic inch displacement engine, such as a Chevrolet 6 cylinder engine, it being understood that more air would be required for larger displacement engines. In the example, my catalytic converter system set forth in my said copending application Serial No. 27,721 is employed for oxidizing the unburned hydrocarbons and carbon monox-

2

ide by combined direct ignition burning and catalytic oxidation.

In tests made with such equipment, at engine idle speeds of about 450 r.p.m., my catalytic converter system has been found to require from about 1½ to 2 cubic feet of air per minute. At this time the amount of excess air which is added to the exhaust system is a relatively large percentage of the exhaust volume, which is on the order of about 6 cubic feet per minute.

10 However, when the automobile is in high speed operation, such as in freeway driving at about 65 miles per hour or more, the hydrocarbon and carbon monoxide content of the exhaust is relatively low, so that the excess air added to the exhaust need be only a very small percentage of the 15 exhaust volume to perform its function of oxidizing these small percentage components. In the present example, with the engine in properly regulated condition, the amount of added air required is only from about 2 to 3 cubic feet per minute at high speeds. Under such relatively high speed operation, the volume of exhaust gases may exceed 100 cubic feet per minute. If quantities of air in excess of about 3 cubic feet per minute are added, then the excess air serves no beneficial function of oxidizing unwanted exhaust components, but does have a detrimental effect of cooling the catalytic converter.

20 At the time of high speed operation the exhaust gases, undiluted with cold air, will reach 1200° F. to 1300° F. temperature, and with about 2 cubic feet per minute of injected air will be quenched to about 1150° F. Larger amounts of air would reduce the temperature proportionally. At the time of this high speed operation, it is not important that the temperature be abnormally high because hydrocarbon and carbon monoxide contents are down close to acceptable quantities. However, if at such 25 time air is added to the exhaust stream to give a temperature of about 850° F. to 900° F., then when deceleration, idle or heavy acceleration follows, and hydrocarbon and carbon monoxide quantities are accordingly both raised to a relatively high level, the catalyst temperature in the catalytic converter (particularly if the converter has been used on the road for an extended period) would be too low to spontaneously ignite the carbon monoxide, which is actually the highest source of burning heat. Since the exhaust gases under deceleration or idle are down at a temperature of only about 400° F., the catalyst bed without the benefit of the burning carbon monoxide would then rapidly cool and the exhaust gases would not be properly treated.

30 This problem of providing only a relatively small increase in the compressor output flow over a wide input speed range of the rotary power source which drives the compressor is further complicated by large variations in the exhaust pressure, and hence in the back pressure on the compressor output, such back pressure not being a direct function of the engine speed. For example, in 35 tests wherein one of my catalytic converters was embodied in the exhaust system, where the automobile was running on the level at 40 miles per hour the back pressure was only equivalent to about 10 inches of water, while when the car was climbing a grade at full throttle at 40 miles 40 per hour the back pressure was equivalent to about 60 inches of water, despite the fact that the engine speed was approximately the same.

45 Prior attempts to limit the compressor output to within the relatively narrow range required for efficient oxidizing of the hydrocarbons and carbon monoxide in the exhaust system have included slip-clutch drives for providing rotary power to the pump, and also pump output pressure bypass valve means for diverting the flow of excess air from the pump. However, heretofore such devices 50 have not been capable of controlling the output to within the required narrow range or of keeping the effects of

back pressure variations from causing substantial unwanted changes in the amount of air provided by the compressor to the exhaust line.

In view of the foregoing and other problems in the art, it is an object of the present invention to provide a novel air compressor and means for regulating the output thereof wherein the air output rate will increase only a relatively small amount for a relatively large increase in the speed of a rotary power source driving the pump.

Another object of the present invention is to provide an air compressor-regulator combination which will not only have an output air flow rate that increases within relatively narrow limits for relatively wide increases in the speed of a rotary power source driving the compressor, but which is also relatively immune from large variations in back-pressure loading on the pump output.

A further object of the present invention is to provide a novel air pump and means for regulating the output thereof which have particular utility in combination with anti-smog apparatus associated with an internal combustion engine for oxidizing unburned hydrocarbon and carbon monoxide components of the engine exhaust, the compressor output being connected to the exhaust system to provide fresh air to assist in the oxidation.

It is also an object of the present invention to provide output regulating means for an air compressor of the character described which includes a regulator valve associated with the pump inlet and having a floating valve element that rests in a lowermost position at low pump speeds permitting relatively free flow of inlet air to the pump, and which rises upon a predetermined inlet flow rate to an uppermost position wherein the floating valve element provides a restricted inlet orifice which limits the volume of air pumped upon further increases in the pump speed.

Another object of the invention is to provide an air pump of the character described having air flow regulating means associated therewith which combines an inlet regulator valve having a floating valve element with a slip-clutch drive connection between the internal combustion engine and the pump shaft, the slip-clutch having a minimum of slippage at low engine speeds and considerable slippage at relatively high engine speeds, this combined regulating means being effective to limit the air outflow of the pump to within a desired narrow increase for large increases in engine speed, with a minimum of effect from exhaust back pressure.

Further objects and advantages of the present invention will appear during the course of the following part of the specification wherein the details of construction and mode of operation of a preferred embodiment are described with reference to the accompanying drawings, in which:

FIG. 1 is an elevational view showing an internal combustion engine and associated exhaust system to which an air compressor and regulator in accordance with the present invention are operatively connected.

FIG. 2 is a side elevation view of an air pump embodying the regulator valve and slip-clutch drive of the present invention.

FIG. 3 is an end elevation view of the pump shown in FIG. 2 looking from left to right in FIG. 2.

FIG. 4 is an end elevation view of the air pump looking from right to left in FIG. 2.

FIG. 5 is an axial vertical section taken on the line 5—5 in FIG. 4 showing the internal details of construction of the pump.

FIG. 6 is a cross-sectional view taken on the line 6—6 of FIG. 5 showing details of the slip-clutch assembly.

FIG. 7 is a cross-sectional view along the line 7—7 in FIG. 5 showing details of the pump in the region of the pump cavity.

FIG. 8 is a vertical section illustrating the details of construction of my presently preferred regulator valve for the pump.

Referring to the drawings, in FIG. 1 I have illustrated air pump or compressor 10 as operatively connected to a conventional internal combustion engine 12, pump 10 being driven by the engine fan belt 14. Although pump 10 is shown as being driven off of the inside of the fan belt, it may be driven by either the inside or the outside of the fan belt, and may, if desired, be conveniently mounted on a vehicle generator which is likewise driven by the fan belt 14.

Fresh air is provided to the pump inlet port through an air inlet conduit 16 which preferably extends from the engine air filter 18 to the pump inlet. Inlet conduit 16 may, if desired, comprise a plastic hose. By thus taking the fresh air from the air filter, pump noise is substantially eliminated and filtered air is fed to the pump unit. only a very minor vacuum is caused by the air filter and the inlet conduit 16 so that the fresh air provided to the pump is substantially at atmospheric pressure. The air inlet conduit 16 is operatively connected to pump regulator valve 20 which is, for convenience, preferably mounted on one end of the pump 10.

The pump 10 provides air through pump output conduit 22 to the engine exhaust pipe 24, preferably introducing the air into exhaust pipe 24 just downstream of the exhaust manifold 26. Output conduit 22 preferably includes a check valve 28 to protect pump 10 from exhaust gases in the event of pump failure. If desired, the check valve may be provided immediately adjacent to or as a part of the air pump 10, and may comprise a diaphragm of neoprene or flexible plastic with a valve "base" or seat upstream of the diaphragm comprising a part of the pump discharge port. The downstream side of this diaphragm is connected to output conduit 22 at a properly shaped fitting which is easily removable for replacing or inspecting the conduit 22.

The pump output conduit 22 may, if desired, comprise copper tubing, an internal diameter for such tubing of about $\frac{3}{8}$ of an inch appearing to be adequate for this conduit. Alternatively, the output conduit 22 may be at least partly composed of plastic hose from the air pump 10 to a point closely approaching the entrance to exhaust pipe 24, with metal forming the portion of output conduit 22 immediately adjacent to the exhaust pipe. With this construction, in case of failure of the check valve 28, the plastic hose will melt and discharge any hot exhaust gases, thereby protecting both the compressor and the check valve.

FIG. 1 of the drawings illustrates the embodiment of air pump 10 in connection with an internal combustion engine employing the catalytic converter system shown, described and claimed in my said copending application Serial No. 27,721. In this arrangement, catalytic case 30 is operatively connected to the exhaust pipe 24 at the front end of case 30, with the decontaminated exhaust gases passing out of the rear end of converter case 30 and through tail pipe 32. Spark plug 34 is disposed in the exhaust line just ahead of the catalytic converter case 30 for direct ignition of the exhaust-air mixture prior to the catalytic oxidation in converter case 30, this direct ignition not only accomplishing part of the oxidation of the unburned hydrocarbons and carbon monoxide in the exhaust stream, but also heating up the exhaust gases to a point where the catalyst in the converter case 30 will function most efficiently. The required high voltage interrupted electricity for spark plug 34 is provided by spark coil 36 through a suitable electrical conductor 38, the primary current for coil 36 being interrupted as required by suitable interrupter points 40 which are preferably mounted on air pump 10 so as to be actuated by a cam member on the pump shaft.

As aforesaid, the principal purpose of the present invention is to provide regulating means for controlling the air output of pump 10 which will restrict the increase in the air output of the pump to a relatively small amount for relatively large increases in engine speed, so that the

air output of pump 10 will closely match the air requirements of the catalytic converter system. Thus, in the example previously given, for engine idle speeds of about 450 r.p.m., the converter system requires between about 1½ and 2 cubic feet of air per minute, while at highway speeds of the order of 65 miles per hour and above, when the engine is rotating at about 2500 r.p.m. or faster, the air requirement is only between about 2 and 3 cubic feet per minute (these figures being for a 235 cubic inch displacement engine such as a Chevrolet 6 cylinder engine, with larger displacement engines requiring proportionally more air). In order to accomplish this desired regulation of the air output of pump 10, I have found it preferable to combine two control devices with the air pump, namely, (1) the slip-clutch best shown in FIGS. 5 and 6 of the drawings, and (2) the regulator valve best shown in FIGS. 2 and 8 of the drawings.

The slip-clutch drive employed in pump 10 has the desirable characteristic of greatly increased slippage with increases in engine speed, thereby maintaining only a small increase in pump air output at high speeds over that at low speeds. Also, this slip-clutch drive, by permitting only a small amount of increase in the pump speed for high engine speeds as compared with the pump speed for low engine speeds, keeps the pump operating within a speed range which will involve a minimum of wear and tear in the pump, and will actually prevent rotor blade breakage, pump speeds above 4000 r.p.m. usually destroying or causing rapid erosion of the carbon blades normally used in a positive displacement pump of the type shown and described herein. Also, it has been found in actual road operation that if the pump has a burned-out bearing or broken blade, the slip-clutch will continue to run and the belt and pump pulley will function normally; where otherwise something must give away, which would result in a burned-out belt or further damage to the pump.

It has been found in practice, however, that the slip drive for the pump, when adjusted so as to rotate the pump at a speed which will not cause blade breakage or undue wear, will produce pump air deliveries ranging from about 2 cubic feet per minute at engine idle speeds to about 5½ cubic feet per minute at high speeds, which is somewhat higher than the air output for optimum catalytic converter operation. It has also been found that the slip drive is to some extent susceptible to exhaust pressure changes, increases in that pressure increasing the load on the pump vanes, resulting in increased slippage in the drive.

By combining the regulator valve 20 in the pump unit, however, I have been able to control the output to the desired range of from about 1.5 to 2 cubic feet per minute at idle to about 2 to 3 cubic feet per minute at high speeds, and I have satisfactorily isolated the pump performance from variations in the back pressure.

Referring now to the specific details of construction of the pump, the pump 10 includes a suitable base member 42 upon which a pair of spaced end plates 44 and 46 are mounted by means of bolts 48 or other suitable means. A cylindrical pump case 50 is supported between end plates 44 and 46 by screws 52 to provide a sealed pumping chamber therein.

Pump inlet port 54 is provided through end plate 46, and is operatively connected to regulator valve 20 through a tubular connector 56. Outlet port 58 is likewise provided through end plate 46, and communicates with the outlet conduit 22.

It will be noted that by providing inlet and outlet ports 54 and 58, respectively, in the end wall rather than in the cylindrical pump case as is the usual procedure, I greatly reduce frictional wear of the ports, and on the pumping vanes, as the ports are not in the area of centrifugally forced engagement of the vanes against the pump case.

Pump shaft 60 is rotatably mounted in sealed anti-friction bearings 62 which are supported in the respec-

tive end plates 44 and 46, and pump rotor 64 is keyed to shaft 60 within pump case 50 between end plates 44 and 46 so as to rotate with shaft 60. Pumping vanes 66 are radially slidably mounted in rotor 64 so as to be engaged in sliding contact with the inner wall of pump case 50 by centrifugal force.

The pump shaft 60 is driven through a circular clutch plate 68 that is mounted on a threaded spindle 70 on one end of pump shaft 60, plate 68 being held in position by nut 72.

Clutch plate 68 is disposed within a clutch housing 74 which is driven by the engine fan belt 14, housing 74 including a pulley portion 76 having an external annular recess 78 therein for receiving the fan belt 14. Clutch housing portion 76 is rotatably mounted on an anti-friction bearing 80 which is supported on a fixed hub 82 extending outwardly from end plate 44 and which is retained on hub 82 by a suitable retaining ring 83. The pulley portion 76 is tapped in several locations near the periphery to accept screws which clamp and retain the remainder of clutch housing 74 to pulley portion 76.

Clutch housing 74 also includes an intermediate housing member 84 and a housing cover member 86, the cover member 86 preferably being finned for cooling purposes and including an axial cup or thimble portion 88 having a grease reservoir 90 therein. Upon rotation of the clutch housing 74, grease disposed therein frictionally engages the clutch plate 68 so as to rotate clutch plate 68 and pump shaft 60. A combination of a proper grease in clutch housing 74 and a clutch plate 68 of the particular construction shown in the drawings and hereinafter described in detail produces relatively low slippage between clutch housing 74 and clutch plate 68 at low speeds, and a large amount of slippage at high speeds, thus providing a pump output range which is only a little greater than that desired.

The clutch plate 68 is provided with a plurality of circularly arranged openings 92 therethrough, preferably six in number, the openings 92 preferably being spaced at equal radial distances from the center of clutch plate 68. A channel recess 94 extends from each opening 92 to the periphery of clutch plate 68 on one side of clutch plate 68, the recesses 94 extending to a depth of approximately one-third the thickness of the clutch plate. Similar channel recesses 96 on the other side of clutch plate 68 extend from the respective openings 92 to the periphery of the clutch plate. The channel 94 from each opening 92 will overlap the channel 96 from an adjacent opening 92, but the channels will not break out into each other since the respective depth of each is only one-third the total thickness of clutch plate 68. A relatively small clearance exists on both sides of clutch plate 68, and a larger clearance exists at the outer edge between clutch plate 68 and clutch housing 74. Grease within clutch housing 74 is thus pumped or circulated by clutch plate 68 through the channels 94 and 96, utilizing the larger clearance between the outer edge of clutch plate 68 and clutch housing 74 as a reservoir for the grease in transit, limiting the tendency to increase frictional engagement at this point during high speed operation.

A high temperature silicone grease has been found satisfactory for use in the clutch housing, providing an increase of from about 1½ to 2 cubic feet per minute to about 5 cubic feet per minute of pump air output for an engine speed range of from about 450 r.p.m. (idle speed) to 2500 r.p.m. (highway speed), where the pump is operated without the benefit of the regulator valve 20. Variations in this relationship between pump air output and the driven speed of the pump may be accomplished by varying the amount of side clearance of the clutch plate 68 in clutch housing 74, which is preferable within a range of from about 10 to about 50 thousandths of an inch, and by controlling the thickness or centipoise of the grease employed.

It is preferred to employ a type of grease which will

have a characteristic of thixotropy; that is, one which will function principally as a solid until a certain shear point is reached, and thereafter will function primarily as a liquid. Silica which is powdered to a fineness of less than 1 micron in particle size exercises this property when mixed with a suitable carrier liquid such as water or oil. Other materials which will perform in this manner are finely powdered "Santocel" produced by Monsanto Chemical Company and finely powdered "Kaolin" produced by Minerals and Chemicals Corporation. Finely powdered silica appears to be preferred as it does not attrite by grinding itself. Also very small concentrations of Guar, such as "Jaguar," a commercial gum resin, will promote thixotropy, so that small quantities of such material may be employed.

I find it convenient to mount the interrupter points 40 on the outside of pump end plate 46, and to provide a multi-lobed cam member 98 on the end of pump shaft 60 which projects outwardly through end plate 46 for producing the vibratory motion required for the interrupter points 40. The points 40 include a movable contact member 100 and a fixed contact member 102, the movable contact member 100 being spring-biased against the cam member 98 to provide the desired interruption of the points.

The purpose of interrupter points 40 is to provide a means of interrupting the direct current to the primary winding of the conventional automotive ignition coil 36, enabling the coil to then step-up the primary voltage to a secondary voltage sufficient to fire the ignition spark plug 34. A typical installation would find fixed contact member 102 electrically grounded to pump end plate 46, and movable contact member 100 insulated from end plate 46 and connected externally to the primary coil winding. A capacitor may be used "across" interrupter points 40 if desired, both for the elimination of metal transfer and for the more satisfactory operation of the ignition system which includes the spark plug 34.

Referring to FIGS. 2 and 8 of the drawings, I will now describe a presently preferred embodiment of the regulator valve which cooperates with the slip-clutch drive to provide the desired air output of the pump.

The regulator valve 20 includes a vertically arranged tubular valve housing 104 which is preferably supported on the pump casing as by means of a supporting bracket 106 that extends around valve housing 104 and is attached to pump end plate 46 by one or more screws 108.

The regulator valve 20 includes a bottom end closure 110 which extends across the lower end of tubular valve housing 104, with valve inlet port 112 extending through bottom end closure 110 and communicating with a suitable inlet fitting 114 attached to end closure 110. The air inlet conduit 16 is operatively connected to inlet fitting 114 by conventional means.

Disposed across the inside of valve housing 104 above bottom end closure 110 is a screen spacer member 116 upon which a floating valve element 118 normally rests. Valve element 118 is preferably of the ball type, and is suitably smaller than the inside diameter of valve housing 104. The valve element 118 is spaced sufficiently above inlet port 112 by the screen 116 to permit incoming air to pass freely through port 112 and around valve element 118 upwardly through valve housing 104 when ball valve element 118 is in its lowermost, rest position against screen 116. It will be apparent that other suitable spacer means may be provided in place of the screen 116, which is merely the presently preferred means for this purpose.

A top end closure member 120 completely closes off the upper end of the tubular valve housing 104, and a valve outlet port 122 extends through the wall of housing 104 just below top end closure 120. A suitable valve outlet fitting 124 communicates with port 122 to provide for attachment of the outer end of tubular connector 56, whereby valve outlet air will pass out of the upper end of

valve housing 104 through outlet port 122 and fitting 124, and then will pass through tubular connector 56 to the pump inlet port 54.

A wall 126 extends across valve housing 104 below outlet port 122, the wall 126 being provided with an orifice 128. An adjusting screw 130 is threaded into top end closure 120, extending downwardly through valve orifice 128. By this means, when the air flow increases beyond a certain minimum flow, it will blow the floating ball valve element 118 upwardly until valve element 118 is stopped by the lower end of adjusting screw 130. The ball will remain in this position so as to define a more restricted valve orifice until the air flow drops below the said predetermined minimum flow, at which time the ball will again fall down against the screen 116, removing the restriction from valve orifice 128.

In the example previously given, where the desired pump output ranged from about 1½ to 2 cubic feet per minute at idle engine speeds to between 2 and 3 cubic feet per minute at highway speeds, the relative sizes of the ball valve element 118 and the tubular valve housing 104 are preferably such that when the input air flows at 2 cubic feet per minute or less, the valve element 118 will rest on screen spacer 116 at the bottom of tubular housing 104, but when the air flow rate increases to in excess of 2 cubic feet per minute, the ball valve element 118 will rise and be air-borne, seating against the bottom of adjusting screw 130 adjacent valve orifice 128. The ball valve element 118 will remain in this position until the air flow again decreases to below about 2 cubic feet per minute, at which time the ball will drop down against screen 116 and orifice 128 will be unrestricted.

I have found in practice that by properly adjusting the screw 130, the ball valve element 118 can be positioned relative to orifice 128 so as to control the air flow to only slightly in excess of 3 cubic feet per minute at high engine speeds. The compressor at high speeds, in effect, is under a partial vacuum or suction which varies from substantially zero at 2 cubic feet per minute to higher vacuums as the speed is increased. Back-pressure loading upon the compressor from the engine appears to have no effect upon the air delivery of the compressor to the exhaust system above 2 cubic feet per minute, as such back pressure only affects the degree of clutch slippage, which 2½ cubic feet per minute air flow merely affects the amount of suction at the pump inlet.

While the instant invention has been shown and described herein in what is conceived to be the most practical and preferred embodiment, it is recognized that departures may be made therefrom within the scope of the invention, which is therefore not to be limited to the details disclosed herein, but is to be accorded the full scope of the claims.

I claim:

1. Apparatus for removing impurities from an internal combustion engine exhaust system which comprises: an exhaust conduit; means in said exhaust conduit for oxidizing exhaust ingredients not previously oxidized in the engine; and air injection means connected to said exhaust conduit for introducing air into said exhaust conduit to provide a mixture of air and exhaust ingredients, said air injection means including an air pump having a housing with air inlet and outlet ports, a rotor member rotatably mounted in the housing for drawing air in through said inlet port and pumping the air out through said outlet port, rotary power input means rotatably mounted in the housing and connected to the rotor for driving the rotor, and an airflow regulator valve connected to said pump inlet port, said regulator valve including a body having a passage therein, an air inlet opening and an air outlet orifice in the body communicating with said passage, air conduit means connecting the orifice to the pump inlet port, a valve element of smaller cross-section than said passage disposed in said passage between said inlet opening and said orifice, and movable between an open position spaced from said orifice and

a closed position adjacent to said orifice in which the valve element partially restricts the orifice, said valve element being normally biased toward its said open position, whereby when the flow of pump input air through said valve is below a predetermined rate the valve will be in its open position and the air will have relatively unrestricted passage through the valve, and when the flow of pump input air is above said predetermined rate the air will blow the valve element to its said closed position at which the valve element will restrict the flow of air through the orifice.

2. Apparatus as defined in claim 1 wherein said oxidizing means includes direct ignition means in said exhaust conduit downstream of said air injection means for igniting exhaust ingredients not previously completely oxidized, and catalytic oxidizing means connected to said exhaust conduit downstream of said direct ignition means for oxidizing exhaust ingredients not previously completely oxidized.

3. Apparatus as defined in claim 2 wherein said connection between said rotary power input means and said rotor is a slip-clutch drive connection.

4. Apparatus as defined in claim 3 wherein said rotary power input means comprises a clutch housing rotatably mounted on the pump housing, and said slip-clutch drive connection includes a clutch plate within said clutch housing, said clutch plate being connected to the rotor so that the clutch plate and rotor rotate together; and thick fluid material in the clutch housing for imparting rotation from the clutch housing to the clutch plate.

5. Apparatus as defined in claim 4 wherein said biasing is accomplished by vertical arrangement of said passage with said inlet opening communicating with the passage below said orifice, the valve element being urged by gravity toward its said open position.

6. Apparatus as defined in claim 5 wherein said valve element is a ball loosely disposed in said passage.

7. Apparatus as defined in claim 4 wherein said thick fluid has the characteristics of thixotropy.

8. Apparatus for removing impurities from an internal combustion engine exhaust system which comprises: an exhaust conduit; means in said exhaust conduit for oxidizing exhaust ingredients not previously oxidized in the engine; and air injection means connected to said exhaust conduit for introducing air into said exhaust conduit to provide a mixture of air and exhaust ingredients, said air injection means including an air pump having a housing with air inlet and outlet ports, a rotor member rotatably mounted in the housing for drawing air in through said inlet port and pumping air out through said outlet port, rotary power input means rotatably mounted in the housing and connected to the rotor for driving the rotor, and an airflow regulator valve connected to said pump inlet port, said regulator valve including a body having a passage therein, an air inlet opening and an air outlet orifice in the body communicating with said passage, said passage extending upwardly from said inlet opening to said orifice, air conduit means connecting the orifice to the pump inlet port, a valve element of smaller cross-section than said passage disposed in said passage and movable between a lowermost position spaced above said inlet opening and an uppermost position adjacent to said orifice in which the valve element partially restricts the orifice, abutment means in said passage against which

5 the valve element seats in its lowermost position, and stop means adjacent to said outlet orifice against which the valve element seats in its uppermost position, whereby when the flow of pump input air through said valve is below a predetermined rate the valve will be in its lowermost position and the air will have relatively unrestricted passage through the valve, and when the flow of pump input air is above a predetermined rate the air will blow the valve element to its uppermost position at which time the valve element will restrict the flow of air through the orifice.

10 9. Apparatus as defined in claim 8 wherein said abutment means is a wire screen extending across said passage above said inlet opening.

15 10. Apparatus as defined in claim 6 wherein said passage is vertically arranged and is cylindrical.

11. Apparatus as defined in claim 8 wherein said stop means is an adjusting screw.

12. Apparatus for removing impurities from an internal combustion engine exhaust system which comprises: an exhaust conduit; means in said exhaust conduit for oxidizing exhaust ingredients not previously oxidized in the engine; and air injection means connected to said exhaust conduit for introducing air into said exhaust conduit to provide a mixture of air and exhaust ingredients, said air injection means including an air pump having a housing with air inlet and outlet ports, a rotor member rotatably mounted in the housing for drawing air in through said inlet port and pumping air out through said outlet port, rotary power input means rotatably mounted in the housing; a slip-clutch drive connection in the pump between said power input member and the rotor, and an airflow regulator valve connected to said pump for regulating the rate of flow of air pumped through said outlet port, said regulator valve including a body having a passage therein, an air inlet opening and an air outlet orifice in the body communicating with said passage, air conduit means connecting the orifice to the pump inlet port, a valve element of smaller cross-section than said passage disposed in said passage between said inlet opening and said orifice, and movable between an open position spaced from said orifice and a closed position adjacent to said orifice in which the valve element partially restricts the orifice, said valve element being normally biased toward

25 its open position, whereby when the flow of pump input air through said valve is below a predetermined rate the valve will be in its open position and the air will have relatively unrestricted passage through the valve, and when the flow of pump input air is above said predetermined rate the air will blow the valve element to its said closed position at which time the valve element will restrict the flow of air through the orifice.

30 35 40 45 50 55 60

6. Apparatus as defined in claim 5 wherein said valve element is a ball loosely disposed in said passage.

7. Apparatus as defined in claim 4 wherein said thick fluid has the characteristics of thixotropy.

8. Apparatus for removing impurities from an internal combustion engine exhaust system which comprises: an exhaust conduit; means in said exhaust conduit for oxidizing exhaust ingredients not previously oxidized in the engine; and air injection means connected to said exhaust conduit for introducing air into said exhaust conduit to provide a mixture of air and exhaust ingredients, said air injection means including an air pump having a housing with air inlet and outlet ports, a rotor member rotatably mounted in the housing for drawing air in through said inlet port and pumping air out through said outlet port, rotary power input means rotatably mounted in the housing and connected to the rotor for driving the rotor, and an airflow regulator valve connected to said pump inlet port, said regulator valve including a body having a passage therein, an air inlet opening and an air outlet orifice in the body communicating with said passage, said passage extending upwardly from said inlet opening to said orifice, air conduit means connecting the orifice to the pump inlet port, a valve element of smaller cross-section than said passage disposed in said passage and movable between a lowermost position spaced above said inlet opening and an uppermost position adjacent to said orifice in which the valve element partially restricts the orifice, abutment means in said passage against which
